(57) **CLAIM**

The ornamental design for a shoe, as shown and described.

DESCRIPTION

FIG. 1 is a bottom perspective view of a shoe in accordance with the new design;

FIG. 2 is a bottom view thereof;

FIG. 3 is a top view thereof;

FIG. 4 is a right side view thereof;

FIG. 5 is a left side view thereof;

FIG. 6 is a front view thereof; and,

FIG. 7 is a rear view thereof.

The shoe upper shown in broken lines in FIGS. 1-7 shows the portions of the article that form no part of the claim. The broken lines shown in each arch area of FIGS. 1 and 2 along with the broken line around the periphery of FIG. 3, represent boundaries of the design with the lines themselves and the areas within them forming no part of the claim.
